UNITED STATES PATENT OFFICE.

LAURENCE SCOFIELD HOLMBOE, OF OKLAHOMA, OKLAHOMA.

TALKING-MACHINE.

1,312,250.

Specification of Letters Patent. Patented Aug. 5, 1919.

Application filed March 10, 1916. Serial No. 83,875.

To all whom it may concern:

Be it known that I, LAURENCE S. HOLMBOE, a citizen of the United States, and a resident of Oklahoma, in the county of Oklahoma and State of Oklahoma, have invented an Attachment or Improvement in Talking-Machines, of which the following is a specification.

This invention is an improvement in talking machines and has particular reference to a machine of the disk type wherein a reproducer carrying arm is operated to move transversely across a record during the reproduction thereof.

An object of the invention is to provide a mechanism automatically operated, at the conclusion of the reproduction of a record, to raise the sound box or reproducer from engagement with the record and return the same, together with the tone arm, to its original or starting position, whereupon the sound box is again lowered and the stylus caused to engage the record groove. To this end, there is provided a tone arm actuated 25 latching member which is thrown to a releasing position, when the sound box has traversed the record groove, to permit the rotation of a disk or similar element. This rotation of the latter member is designed to operate a lever and cause the same to engage a lifting arm which raises the sound box from the record and then, through the medium of the further movement of the lever, swings the same, together with the tone arm, to its original position with the sound box still elevated. Still further movement of the said lever releases said lifting arm and allows the reproducing stylus to be lowered into contact with the record 40 after which the rotary disk is automatically stopped by engagement with said latching member and the parts are in position for another operation.

Moreover, the invention has for another object the provision of novel mechanism for automatically reproducing several records successively without the necessity of removing and replacing a record after the completion of its reproduction. In carrying out this object the invention provides a supporting arm secured to the machine above the turn-table and in which are mounted several records in superimposed relation. A contact member is mounted in the path of movement of the tone arm, as the same is being returned to normal position, and is

actuated, through suitable connections, to give the shaft, to which are secured a number of record supporting members, a partial rotation. Each record is provided with 60 openings or slots of substantially the same shape as the supporting members whereby, as the shaft is rotated, the members will register with said slots in the lowermost record and permit the same to drop onto 65 the turn-table of the machine. The entire mechanism is arranged so that the record is dropped just previous to the return of the sound box to its original position.

It is also proposed to enable the repetition 70 of the reproduction of a record several times, and this is accomplished by advancing or rotating each record a certain distance, so that the slots in the lowermost record will not register with said members until the 75 desired number of repetitions have been made.

The inventive idea involved is capable 80 of receiving a variety of mechanical expressions, one of which, for the purpose of illustrating the invention, is shown in the accompanying drawings; but it is to be expressly understood that said drawings are merely 85 for the purpose of facilitating the description of the invention as a whole, and not to define the limits thereof; reference being had to the appended claims for this purpose.

In the drawings:—

Figure 1 is a plan view of the apparatus, the sound box being shown, in full lines, as 90 nearing the completion of a reproduction and, in dotted lines, as approaching the opposite extremity of its movement.

Fig. 2 is a side elevation, the parts being 95 shown as in full lines in Fig. 1.

Fig. 3 is a detail showing the position of 100 the sound box lifting device and parts for actuating the same, said device being in the position assumed while the sound box is reproducing a record.

Fig. 4 is a view similar to Fig. 3 showing the parts in the position assumed just after the sound box has traversed the entire record groove.

Fig. 5 is a view similar to Fig. 2 showing 105 the parts in the position assumed at the beginning of the actuation of the sound box lifting device.

Fig. 6 is a side elevation showing the parts in the position when the tone arm has 110 reached the dotted line position shown in Fig. 1.

Fig. 7 is a side elevation and diagrammatic view of certain of the parts when the sound box is in the position shown in Fig. 6.

Fig. 8 is a view similar to Fig. 7 when the parts are in the position just previous to the relowering of the sound box toward the turn-table of the machine.

Fig. 9 is a slightly enlarged view similar to Fig. 7 showing the adjustability of a certain part when employing different sized records.

Fig. 10 is a section on the line 10—10 of Fig. 1.

Figs. 11 and 12 are sections on the lines 11—11 and 12—12 of Figs. 2 and 6, respectively.

One form of the invention, illustrated in the drawings, is so constructed that the same may be readily applied to certain talking machines now commonly used, which include the usual turn table 15 upon which are supported the different disk records, the swinging tone arm 16, and the sound box or reproducer 17 having the usual stylus 18.

The invention consists of a shaft 19 having a suitable connection with the usual motor (not shown) for operating the machine and said shaft is rotated and held stationary, when desired, through the medium of any suitable clutch mechanism also associated therewith but not shown in the drawings. The shaft 19 is mounted in a suitable support 20 and has secured to one end thereof a rotatable disk 21 having a shoulder 22 on its periphery. When the parts are in the position shown in Fig. 3 a latching member 23, pivoted at 24 to the support 20, has a shoulder 25 in engagement with the shoulder 22 on the disk 21 and a small spring 26 retains said latching member in this position so as to prevent rotation of said disk and consequent rotation of the shaft 19.

Means are provided for lifting the sound box 17 from engagement with the record at the completion of the reproduction thereof and consist of a sound box lifting device 27 in the form of lever pivoted at 28 to an arm 29 extending from the main portion of the tone arm 16. One end 30 of the lifting device 27 engages the under side of the goose neck of the sound box while the other end is curved as indicated at 31 and adapted to be engaged at the completion of a reproduction by an angular piece 32 carried by the upper end of the lever 33. In order to permit of this engagement and consequent actuation of the sound box lifting device 27 the tone arm 16 has secured thereto a contact member 34 which, after the stylus 18 has traversed the record groove, engages or contacts with the latching member 23 and thrusts the same to the position shown in Fig. 4 whereupon the shoulders 22 and 25 are disengaged and the disk 21 permitted to rotate. It is to be noted that at the beginning of the rotation

of said disk the reproducer or sound box lifting device is in engagement with the end 32 of the lever 33, as shown, and remains until the parts assume the position shown in Fig. 8. The disk 21 is provided with the laterally extending pin 35 which engages in the slot 36 formed in the lever 33, said lever being also provided with another slot 37 at its lower end into which projects a pin 38 carried by the support 20. As the rotation of the disk 21 continues the pin 35 engages the lower end of the slot 36 and causes the end 32 of the lever 33 to describe a predetermined path of movement, as shown in Fig. 7, with the assistance of a cam member 39 adjustable by means of an arm 40 to the dotted line position shown in Fig. 9 when it is desired to reproduce larger records. This cam member 39 includes spaced elements, the upper one adjustable, which provide a slot 41 therebetween and a pin 42 carried by the lever 33 engages under the lowermost element of the cam, as shown in Fig. 7, just after the disk 21 has started to rotate. The lower end of the lever 33 containing the slot 37 is forced downwardly, during this movement, against the tension of a spring 43 until the upper end of said slot 37 is in engagement with the pin 38 whereupon said pin will act as a fulcrum for said lever for a short space of time. Upon reaching the farther end of the lowermost element of the cam 39 the pin 42 will ride over said end and, by reason of the tension of the spring 43 secured to the lower end of the lever 33, said pin will be caused to engage the upper element of the cam 39 and be forced into the slot 41 between said elements. Continued rotation of the disk 21 will swing the lever so that the pin 42 will move to the other end of the slot 41 until disengaged from the upper element of the cam 39. Up to this time it will be seen that the sound box or reproducer lifting device 27 has been adjusted to its lifting position, as shown in Figs. 5 and 6, and that the same remains in this position throughout the movement of the lever 33 and consequent movement of the tone arm 16 to its original or starting position. When the pin 42 disengages from the slot 41, the spring 43 will cause the upper end of the lever 33 to suddenly take an upward vertical course, as clearly shown in Fig. 7, whereupon the lifting device 27 will be lowered and permit the stylus 18 of the sound box to again engage a record surface. It will thus be seen from this description that at the completion of the reproduction of a record the stylus sound box is automatically lifted from engagement therewith and said sound box and tone arm are swung to their original or starting positions whereupon the stylus may be engaged with the record and the reproduction thereof repeated as many times as desired.

By referring to the dot and dash line in Fig. 7 indicating the movement described by the upper end of the lever 33 it will be noted that the portion of the line between the vertical portion thereof and the dotted line position of said lever is the space traversed by the tone arm 16 as the same is moving transversely across the record during the reproduction thereof.

10 The invention also contemplates the automatic reproduction of several records in succession, and to this end there is provided a substantially U-shaped frame 44 which is preferably secured to the casing of the machine and overhangs the turn-table 15 thereof. The horizontal member of the frame 44 has extending laterally therefrom an arm 45 on which is mounted a reciprocating member 46 having a slot 47 adjacent its outer end for receiving therein a pin 48 carried by the outer end of said arm 45. The outer extremity of the reciprocating member 46 is provided with a depending contact rod 49 which is engaged by a portion of the tone arm 16 when the same is being moved to its original or starting position whereby said member 46 is adjusted to the full line position shown in Fig. 1 against the tension of a spring 50, the limit of said movement being assumed when the tone arm is in the dotted line position as shown in Fig. 1 just previous to the return thereof to the original position. The other extremity of the member 46 is provided with a small extension 35 or pawl 51 which, as the member is being moved as just described, engages one of the teeth of the ratchet wheel 52 which is secured to the upper end of a vertical shaft 53 thus giving said shaft approximately one- 40 twelfth of a revolution, as shown in the drawings.

The shaft 53 is mounted directly over the central post of the turn-table upon which the records are mounted and has extending therefrom, intermediate its ends, a number, preferably three, record supporting arms 54, 54' and 54'' having small anti-friction rollers 55 carried by the extremities thereof, said rollers being adapted to engage the bottom face of the lowermost of a plurality of superimposed records 56. The supporting arms are preferably provided with depending spiral extensions 57 the purpose of which is to cause the record to rotate as the same is being lowered onto the turn-table 55 whereby said record will be rotated with approximately the same speed as the turn-table when the same engages thereon, thus preventing undue friction. Moreover, such rotation of the record 56 as the same is being lowered along the shaft 53 will, by reason of the centrifugal action, prevent the same from dropping with too great a force upon the turn-table. The horizontal portion of the frame 44 also has depending

therefrom a stop pin 58 which engages in one of a number of openings 59 formed in the records 56 whereby said records are prevented from turning until the same have dropped below the lower extremity of the pin.

In order to readily permit of the records being lowered onto the turn table the same are each provided with radially extending slots or openings 60, 60', and 60'', corresponding in number to the number of record supporting arms and of substantially the same shape as said arms but of slightly larger proportions so that when the shaft 53 is rotated and one of the arms is brought into registration with its particular opening or slot the record will be lowered. In the embodiment shown in the drawings provision is made for mounting three records upon the supporting arms and the parts for rotating the shaft 53 are adjusted so that said shaft is given one-twelfth of a revolution when actuated thereby. In order to avoid confusion in the illustration of the invention, as shown in Fig. 11, the slots for only the lowermost and the next superimposed records are shown, respectively in dotted and full lines. Referring to Fig. 11 it will be seen that when the shaft 53 is rotated in a clock-wise direction the supporting arms 54, 54' and 54'' will rotate one-twelfth of a revolution, as previously stated, and will then be in registration with the slots 60, 60' and 60'', shown in dotted lines which will permit of the record being lowered. The position of the record as just described is also clearly illustrated in Fig. 12. Upon the lowering of the lowermost record the next superimposed record will be lowered by gravity onto the supporting arms and when the shaft 53 is next actuated as previously described, the same operation will take place. Should it be desired to repeat the reproduction of a record which is mounted upon the turn-table of the machine, the superposed records are advanced, by hand, in a clockwise direction, either one-twelfth or two-twelfths of a revolution according to whether or not it is desired to have one or two repetitions. Thus by moving the lowermost record from the dotted line position of the slots, as shown in Fig. 11, to the full line position thereof and in turn adjusting the next superimposed records to one position in advance of their original locations it will be seen that the supporting arms, when rotated, will not register with the slots of the lowermost record and the same will not, therefore, be lowered onto the turn-table. The repeating action of the tone arm and sound box, as previously described, will still take place and the record already on the turn-table will be repeated. Should it be desired to reproduce the record three times, instead of two 130

as just described, the superposed records are advanced another twelfth of a revolution whereupon at the end of the third reproduction the supporting arms will register 5 with the openings in the lowermost record and the same will be lowered onto the turn-table.

What is claimed is:

1. In a talking machine, the combination 10 of the tone arm, a sound box carried thereby, a bracket on the tone arm, a sound box lifting device pivoted on the bracket, a lever disposed in position to be approached by the lifting device and engaged at the end 15 of a reproduction, a revolute member having an operating connection with said lever, for actuating the lever and swinging the lifting device, a latch normally holding the revolute member from rotation, and means 20 on the tone arm for engaging the latch to release said revolute member at the end of a reproduction.
2. In a talking machine, the combination 25 of the tone arm having a sound box pivoted thereon, a sound box lifting device pivoted adjacent to the sound box and having a portion extending to one side, a contact member carried by the tone arm, a lifting lever in position to be approached by the 30 lifting device as the sound box traverses a record, a revolute member having connection with the lifting lever, and a latch normally holding the revolute member inoperative, said latch being in position to be 35 approached by the contact member on the tone arm, and engaged thereby at the completion of a reproduction.
3. In a talking machine, the combination 40 of a swinging tone arm, a sound box carried thereby, a lifting device for the sound box, a lever arranged to be engaged by said lifting device to raise said sound box at the completion of a reproduction, a revolute member with connections for moving said 45 lever to convey said tone arm and sound box to their starting positions, and a latch for retaining the revolute member in inoperative position while the stylus of the sound box is traversing the record groove, and 50 operated by contact with the tone arm, when said groove have been traversed, to release the revolute member.
4. In a talking machine, the combination 55 of a swinging tone arm, a sound box carried thereby, a lifting device for the sound box, a lever actuated to engage said lifting device, to raise said sound box at the completion of a reproduction, automatically operated means for moving said lever to con- 60 vey said tone arm and sound box to their starting positions, and revolving ratchet actuated means operated upon by said tone arm on the return of the tone arm to its starting position, for feeding another record onto the turn-table of the machine.

5. In a talking machine, the combination 70 of a swinging tone arm, a sound box carried thereby, automatically operated means for raising the sound box from engagement with the record at the completion of the reproduction thereof and returning said sound box to its starting position, and pawl and ratchet mechanism operated automatically for dropping another record onto the turn-table of the machine at the completion of 75 the first reproduction and before the arrival of the sound box to its starting position.

6. In a talking machine, the combination 80 of a tone arm, a sound box carried thereby, revolute means for supporting a plurality 85 of records over the turn-table of the machine, automatically operated means for elevating the sound box upon the return of the tone arm to the starting position after the completion of the reproduction of a record, means operated by said return movement to partly revolve the record supporting means to lower one of the superposed records onto 90 said turn-table, and means for retaining the last-named means in inoperative position 95 while the stylus of the sound box is traversing the record groove.

7. In a talking machine, the combination 100 of a turn-table, means for supporting a plurality of records above said turn-table, means automatically operated to lower one 105 of said records onto the turn-table after the completion of the reproduction of the preceding record thereon, and means for revolving said record as the same is lowered.

8. In a talking machine, the combination 110 of a swinging tone arm, a turn-table, means for supporting a plurality of records above said turn-table, means operated by the return of the tone arm to its starting position 105 after a reproduction for lowering one of said superposed records onto said turn-table, and means for revolving said record as the same is lowered.

9. In a talking machine, the combination 115 of a turn-table, a swinging tone arm, a sound box carried thereby, a frame mounted above said turn-table, a rotatable shaft carried by said frame, record supporting arms secured to said shaft, a plurality of records mounted 120 on said arms and provided with openings adapted to register therewith when said shaft is rotated, and means carried by said frame and adjustable relative thereto to rotate said shaft after a completion of the reproduction of a record on said turn-table to permit one of the records supported on said arms to be lowered onto said turn-table.

10. In a talking machine, the combination 125 of a turn-table, a swinging tone arm, a sound box carried thereby, a frame mounted above said turn-table, a rotatable shaft carried by said frame, record supporting arms secured to said shaft, a plurality of records mounted on said arms and provided 130

with openings adapted to register therewith when said shaft is rotated, and means operated, by the return of the tone arm and sound box to their original positions, to rotate said shaft whereby one of the records superposed above the turn-table is lowered onto the same.

11. In a talking machine, the combination of a turn-table, a swinging tone arm, a sound box carried thereby, a frame mounted above said turn-table, a rotatable shaft carried by said frame, record supporting arms secured to said shaft, a plurality of records mounted on said arms and provided with openings adapted to register therewith when said shaft is rotated, means operated, by the return of the tone arm and sound box to their original positions, to rotate said shaft whereby one of the records superposed above the turn-table is lowered onto the same, and means for rotating said record as the same is being lowered.

12. In a talking machine, the combination of a turn-table, a swinging tone arm, a sound box carried thereby, a frame mounted above said turn-table, a rotatable shaft carried by said frame, record supporting arms secured to said shaft, a plurality of records mounted on said arms and provided with openings adapted to register therewith when said shaft is rotated, means operated, by the return of the tone arm and sound box to their original positions, to rotate said shaft whereby one of the records superposed above the turn-table is lowered onto the same, a stop pin carried by said frame and engaging said superposed records to prevent rotation thereof when said shaft is rotated, and means for rotating the record after the slots therein have registered with said supporting arms and the same has been disengaged from said stop pin.

13. In a talking machine, the combination with a swinging tone arm, a sound box carried thereby, a sound box lifting device pivoted to said tone arm, an actuating lever for said lifting device, a rotatable element associated with said lever and adapted to cause the same to engage said lifting device to raise the sound box off of a record after the completion of a reproduction and convey said sound box and tone arm to their starting positions, means for guiding said lever whereby to cause the same to describe a predetermined path of movement, and means for retaining said lever stationary while the stylus of the sound box is traversing a record groove, said means being actuated by the tone arm at the completion of the reproduction to release said lever and permit the rotation of said rotary element.

14. In a talking machine including a traversing sound box, a lifting device pivoted adjacent to the sound box having one end engaging said box and one end free, a

lever adapted to be engaged by said free end at the end of the inward travel of the sound box, an externally driven member for actuating the lever and operating the lifting device to lift the sound box, a latch engaging and holding said driven member from operation normally, and a contact member movable with the sound box for engaging the latch and releasing said driven member at the end of the inward movement of the sound box.

15. In a talking machine including a traversing sound box, a lifting device pivoted beneath the sound box with one end engaging said box, the free end having a hook portion, an automatically actuated lever positioned to be approached by the free end of the lifting device as the sound box travels inwardly, and an angular piece carried by said lever for receiving the hook end of the lifting device.

16. In a talking machine including a traversing sound box and a tone arm, a lifting device pivoted beneath the sound box having one end engaging said box and a free hooked end, a lever arranged to be approached by the sound box as it travels inwardly, an angular piece carried by said lever for receiving said hooked end, an operating disk having a connection with said lever and a shoulder on the periphery, a latch engaging said shoulder and normally holding said disk from operation, and a contact member carried by the tone arm arranged to engage said latch to release the disk simultaneously upon the engagement of the angular piece with said hooked end.

17. In a talking machine including a traversing sound box, a lifting device pivoted beneath the sound box and having a free hooked end, a lever for operating the lifting device, having an angular piece for receiving the hooked end, an operating disk for said lever, a pin carried by said lever, and a cam for guiding the pin and causing the lever and lifting device to move in a prescribed path upon rotation of the operating disk.

18. In a talking machine including a traversing sound box, a lifting device pivoted beneath the sound box and having a free hooked end, a lever for operating the lifting device, having an angular piece for receiving the hooked end, an operating disk for said lever, a pin carried by said lever, a cam for guiding the pin and causing the lever and lifting device to move in a prescribed path upon rotation of the operating disk, and means for adjusting the cam.

19. In a talking machine including a traversing sound box, a lifting device for the sound box including a hooked end, an operating lever having an angular piece engageable with the hooked end, said lever having a medial and an end slot, a pin carried by

the lever, a cam contacting the pin and controlling the movement of the lever, a spring holding the pin in engagement with the cam, and an operating disk having a pin 5 movable in the medial slot.

20. In a talking machine including a traversing sound box, a lifting device for the sound box having a hooked end, an actuating lever for the lifting device including an 10 angular piece engageable with the hooked end, an operating disk having a pin and slot connection with said lever, and a cam located beneath the operating disk with a pin connection with said lever, coacting with 15 said operating disk to move said lever laterally and vertically.

21. In a talking machine including a turn-table, a frame mounted above the turn-table, a rotatable shaft supported on the frame and 20 extending to the turn-table, a plurality of arms mounted on said shaft forming supports for a pile of records, said records having radial slots registrable with said arms, means for turning the shaft and the 25 arms beneath the pile of records, and anti-friction rollers carried by the arms engaging the lowermost record.

22. In a talking machine including a turn-table, a supporting frame, a shaft revoluble 30 on said frame, a plurality of radially extending arms mounted on said shaft for supporting a pile of records, said records having radial slots, means for turning the shaft to move said arms beneath the record pile 35 into registration with the slot in the lowermost record, anti-friction rollers carried by the arms in engagement with the lowermost record, and spirally shaped webs included in the arms for revolving the lowermost record upon release from the pile.

23. The combination with a phonograph, of an attachment to the phonograph for changing and repeating records, consisting of a record supporting frame, record releasing means actuated by the tone arm, pivoted 45 means clamped to the tone arm and adapted to engage and lift the sound box at the end of the record, means arranged to actuate said lifting means at the end of the record, 50 and a contact member clamped to the tone arm, adapted to engage and render said

actuating means operative at the end of the record.

24. The combination with a phonograph including the turn-table and tone arm, of an 55 attachment removably secured to the phonograph casing and the tone arm, consisting of a bracket spanning the turn-table, means pendent from said bracket and supporting a plurality of records, sound box and tone 60 arm returning means mounted on said casing, means mounted on the tone arm for simultaneously rendering said returning mechanism operative and lifting the sound 65 box through the operation of said mechanism, and means mounted on said record support engageable by the tone arm at the end of its return movement, and in operative engagement with said pendent support to partly turn said support to release a record. 70

25. The combination with the turn-table of a phonograph, of a record support spanning the turn-table and secured to the phonograph casing by externally accessible means, a pendent shaft carried by said support in 75 alinement with the central post of the turn-table, a plurality of records carried by the shaft, said records having radial slots disposed out of alinement with each other, and means carried by said shaft beneath the records supporting the pile from the bottom, and susceptible of registration with the radial slots of the lowermost record upon partial revolution of the shaft.

26. The combination with the turn-table 85 of a phonograph, of a shaft in coaxial alinement with the central post of the turn-table, a record pile carried by the shaft, said records having radial slots out of alinement with each other, means engaging the lowermost record and imparting a spiral motion 90 to the lower record upon release thereof by registration of said supporting means with the radial slots therein, and means for partially revolving said shaft to bring said supporting means into registration with said slots.
